E. G. CAMERON, OF TIFFIN, OHIO.

Letters Patent No. 88,007, dated March 23, 1869.

IMPROVEMENT IN FIFTH-WHEELS FOR VEHICLES.

The Schedule referred to in these Letters Patent and making part of the same.

To all whom it may concern:

Be it known that I, E. G. CAMERON, of Tiffin, in the county of Seneca, and in the State of Ohio, have invented certain new and useful Improvement in Fifth-Wheel for Vehicles; and do hereby declare that the following is a full, clear, and exact description thereof, reference being had to the accompanying drawings, and to the letters of reference marked thereon.

The nature of my invention consists in the construction and arrangement of a "fifth-wheel" for vehicles, and in the application of oil-cups to the same.

In order to enable others skilled in the art to which my invention appertains, to make and use the same, I will now proceed to describe its construction and operation, referring to the annexed drawings, which form a part of this specification, and in which—

Figure 1 is a plan view,

Figure 3, a bottom view, and

Figure 2, a section of the oil-cup.

A represents the axle, to the upper side of which the circle B is secured.

The circle B fits in a groove on the under side of the upper circle C, which is provided on its upper side with oil-cups D D, opening in the groove on the under side.

The cups D D are filled with oil, and the stoppers E E are inserted. Said stopper having a thread cut on their lower ends, keep the oil in the cups when screwed tight.

When necessary to lubricate the wheel, slacken the screws, which lets the oil pass out at the lower end, at pleasure.

By this means a perfectly self-lubricating wheel is formed, and one in which all strain and pressure from the king-bolt are removed.

Having thus fully described my invention, What I claim as new, and desire to secure by Letters Patent, is—

The grooved circle C, in combination with the under circle B, and lubricating-cups D D, substantially as and for the purposes herein set forth.

In testimony that I claim the foregoing, I have hereunto set my hand, this 19th day of January, 1869.

E. G. CAMERON.
